BOX OR CARTON

William Brunner, Gas City, Ind., assignor to
Owens-Illinois Glass Company, a corporation
of Ohio

Application December 24, 1932, Serial No. 648,791

2 Claims. (Cl. 229—15)

The present invention relates to improvements in boxes or cartons and particularly those constructed from fiber or paper board.

It is common practice in the art to which the present invention relates where the packaged articles are intended to be separated from each other and occupy individual cells, to arrange within the box or carton a plurality of partitions, said partitions extending the full height or depth of the container. This procedure is followed in packaging bottles and the like articles.

An object of the present invention is the provision of means whereby the height of the partitions may be greatly decreased without adversely affecting their efficiency as separators for the packaged articles. By decreasing the height of these partitions a very material cost reduction is effected and removal of the articles, such as bottles, is facilitated.

Another object is the provision of novel means whereby the partitions although of less height than the carton or box are secured against such movement as would allow contact between any portions of the packaged articles, such as bottles in adjacent cells. To this end vertical spacers which may well be formed by downturned outer ends of two cover flaps, are interposed between the upper ends of certain partitions and the cover, said spacers being of a height corresponding to the difference in height between the partitions and carton. By forming these spacers as just pointed out, rigidity of the carton and resistance to crushing, when they are piled or stacked one upon another, are greatly increased.

Other objects will be in part apparent and in part pointed out hereinafter.

In the drawing:

Fig. 1 is a sectional elevational view taken substantially along the line I—I of Fig. 2.

Fig. 2 is a plan view showing the flaps positioned as illustrated in Fig. 1.

Fig. 3 is a transverse sectional view taken substantially along the line III—III of Fig. 1.

Fig. 4 is a side elevational view with parts broken away and in section showing three sealed cartons stacked one upon the other and illustrating the function of the end flap.

While the invention is shown embodied in a box or carton constructed from fiber or paper board, it is obviously equally well adapted for use in connection with other forms of containers.

The carton C embodying the present invention is of conventional form consisting of pairs of opposed side and end walls 5 and 6 respectively, a bottom 7 and a cover 8, the latter including a

pair of opposed longitudinal flaps 9, and a pair of transverse end flaps 10. Within the carton, vertical partitions 11 of conventional form provide a plurality of separate cells 12 to accommodate the articles being packed. These partitions include a plurality of longitudinal vertically disposed strips 13 having downwardly facing notches 14 into which portions of the transverse strips 15 extend. The above construction is standard and well-known.

A feature of novelty consists in materially reducing the height of the partition with respect to the depth of the carton, the extent thereof, for example, being sufficient to terminate the upper ends of the strips 13 and 15 substantially at the shoulders of bottles or similar articles being packed.

In order that such reduction in the height of the partitions will not result in the shifting of these partitions during handling of the cartons with resultant rubbing contact between the lower portions of the bottles or jars, these partitions are secured against movement in the direction of the length of the bottles by placing vertical spacers 16 between the upper ends of the partitions and cover. One specific form of these spacers which extend transversely of the carton between adjacent transverse rows of the bottles may take the form of a downturned outer end on each end flap 10 of the cover. A score line 17 extending lengthwise of each end flap a distance from the outer end thereof corresponding to the difference in height between the partitions and walls of the carton determines the point of bending of the flap for the purpose stated above.

In packaging bottles or the like in a carton of the above character, all of the cells 12 are filled, the two end flaps 10 are folded inwardly, and the spacers 16 constituting those portions of the flaps outwardly beyond the score lines 17, are projected downwardly between two transverse rows of bottles and brought to rest upon the upper margins of the longitudinal partition strips 13. The longitudinal side flaps 9 are then folded inwardly and secured together by a sealing strip of paper 18, or otherwise. As a result of this construction and assembly, the partitions 11 are secured against movement in the carton and in addition the rigidity of the entire package is increased so that it offers unusual resistance to crushing or distortion in handling and stacking. In this latter respect it will be observed in Fig. 4 that the above described folding of the end flaps will greatly strengthen the structure and contribute materially in resisting external pressure.

which would ordinarily seriously distort the box structure.

Modifications may be resorted to within the spirit and scope of the appended claims.

6. What I claim is:

1. A carton consisting of a bottom, pairs of opposed side and end walls rising therefrom, a closure consisting of pairs of opposed flaps, partitions arranged within the carton to provide 10 article-accommodating cells, said partitions resting upon the bottom and terminating short of the upper end of the carton, and means constituting a part of certain of the flaps for holding the partitions against movement when the carton 15 is sealed, said means comprising spacers formed by bending a portion of the outer end of a pair of opposed flaps vertically downward in horizontal spaced relation into engagement with the upper margin of the partitions and between adjacent rows of articles arranged in the cells and in longitudinal alignment with certain of the partition walls. 90

2. A carton consisting of a bottom, pairs of opposed side and end walls rising therefrom, a closure consisting of pairs of opposed flaps, partitions including vertical walls resting upon the bottom of and arranged within the carton to provide article-accommodating cells, said partitions terminating short of the upper end of the carton, and means for holding the partitions against movement when the carton is sealed comprising spacers formed by bending a portion of the free end of a pair of opposed flaps vertically downward in horizontal spaced relation to each other into engagement with the upper margin of the partitions between adjacent rows of articles arranged in the cells and in longitudinal alignment with certain of the partition walls.
